UNITED STATES PATENT OFFICE.

WILLIAM SMITH, OF EATON RAPIDS, MICHIGAN.

DEVICE FOR FASTENING ON BOOT-STRAPS.

SPECIFICATION forming part of Letters Patent No. 247,219, dated September 20, 1881.

Application filed March 10, 1881. (No model.)

To all whom it may concern:

Be it known that I, WILLIAM SMITH, a citizen of the United States, residing at Eaton Rapids, in the county of Eaton and State of Michigan, have invented a new and useful Device for Fastening on Boot-Straps, of which the following is a specification.

My invention relates to an improvement in the fastening on of the straps by which boots are drawn on, in which the straps are fastened on by a metallic fastener; and the objects of my improvement are, first, to provide a cheap, strong, and durable fastening; second, to afford facility in replacing new straps where the old ones have given out; and, third, to provide a substitute in the place of sewing on the straps with wax-end or thread, in which case it is easily worn out by the friction or contact with the leg or limb of the person, and in which case the wax-end or thread loses much of its tenacity and strength with age, or after once being saturated with water or exposed to the weather.

The accompanying drawings show the means through which I obtain these objects.

Figure 1 is a front view of the fastener as it appears on the outside of the boot-leg. Fig. 2 is an inside front view of the fastener as it appears on the inside of the boot-leg. Fig. 3 represents the fastener in its original form A and B on the boot-leg before the flanges or ends are bent over, forming the fastening C, as in Fig. 1.

The fastener comprises two parts or pieces, 35 the staple B and the clamping-washer A, both

of which are constructed of a malleable metallic substance, and are used or put upon the boot in the following manner: The boot-strap is arranged on the boot-leg in the usual and ordinary way, after which two holes are punched 40 through the boot-leg and boot-strap, attached, at a proper distance apart to let through the ends *x x* of the staple B, as shown in Fig. 3. Now, I take the clamping-washer A, and, pressing down, firmly fit it on the ends *x x* of B, 45 which pass through the hole *i i* of A, as shown in Fig. 3, and which, together with the flanges *y y*, project outward. I now bend the ends *x x* in toward each other, which are short enough so as not to meet, striking down closely with 50 the hammer. Then I bend in the flanges *y y* snugly, which just meet but do not lap, as shown in Fig. 1, thereby preventing the prongs *x x* from straightening out by hard pulling, and at the same time protecting them from any outside obstruction that might happen to come in contact with and break, straighten, or dislocate them.

What I claim as my invention, and desire to secure by Letters Patent, is—

A boot-strap fastener consisting of the staple B and the clamping-washer A, provided with side flanges and end slots adapted to receive and fold over the ends of the staple, all as shown and described.

WILLIAM SMITH.
